UNITED STATES PATENT OFFICE

ALONZO ALDRICH, OF CHICAGO, ILLINOIS

FOURDRINIER PAPER MACHINE

Application filed July 2, 1923, Serial No. 648,960. Renewed January 31, 1927.

My invention relates to Fourdrinier paper machines.

One of the objects of the invention is to provide a simple, practical and advantageous construction of paper making machine, particularly of the Fourdrinier type.

Another object of the invention is to provide a Fourdrinier machine in which the table may be bodily removed in a sidewise manner to permit placing of new wire and may also be adjusted vertically at the feed end to control the flow of paper making material.

Another object of the invention is to provide practical and advantageous mechanism permitting this table removability and feed end adjustability.

Another object of the invention is to arrange for the proper cooperation of the table and pulp holding and feeding devices in the removing and adjusting movements of the table.

Other objects of the invention will appear and be pointed out hereinafter.

In the accompanying drawings, Fig. 1 is a side elevation of a Fourdrinier paper making machine embodying my present invention;

Fig. 2 is a cross section taken on line 2--2 in Fig. 1, showing the table in normal position;

Fig. 3 is a similar view, with the table removed to permit changing a wire;

Fig. 4 is a cross section taken on line 4--4 in Fig. 1, on an enlarged scale;

Figs 5 and 6 are sections taken on line 5--5 and 6--6 respectively in Fig. 4;

Fig. 7 is a side elevation of the feed end of the table and the pulp holding and feeding devices;

Fig. 8 is a cross section taken on line 8--8 in Fig. 7;

Fig. 9 is a cross section taken on line 9--9 in Fig. 7, on an enlarged scale;

Figs. 10 and 11 are cross sections taken on lines 10--10 and 11--11, respectively, in Fig. 8;

Fig. 12 is a sectional view showing tracks 50 and posts; and

Fig. 13 is a cross-section taken on line 13--13 in Fig. 12.

Referring to the drawings, I show a Fourdrinier machine having a main table portion 1 supporting rolls 2 for the wire 3. An additional or supplemental end portion 1^a is also embodied in the machine shown, the same supporting vacuum boxes 5--5 and 6--6, and having a jointed connection, as by pivot 7, with the main portion 1, and also having rolls 8--8 and 9--9 for the wire.

The table comprising the sections or portions 1 and 1^a is adapted for bodily removal in a sidewise manner, to permit the advantageous application of a new wire after a used one has been removed. To such end provision is made for moving the table out and back sidewise on tracks 11, 12 and 13, the table being shown in normal position in Fig. 2, and moved out on said tracks in Fig. 3. The table is provided with suitable power mechanism for moving it out and back on said tracks, as for example, an electric motor 15, (Figs. 1 and 5) power-connected by spur wheel 16, gear 17, worm 18, and wheel 19 with driving shaft 20 carrying wheel 21 for track 13, said shaft 20 being coupled to shaft 20^a carrying wheels 22 and 23 for tracks 11 and 12, respectively. The rear or back side of the table is provided with wheels 25--25 (Figs. 2, 4 and 6), for traveling on the tracks 11, 12 and 13, said wheels 25 being preferably constructed, as shown in Fig. 6, with outside portions 25^b--25^a, for purposes to be described later.

Tracks 11, 12 and 13 are made in two sections and of such length as to provide for the table in both out and in positions and are supported by posts or pedestals 26, 27, 28 and 29. Posts 27 have means such as bolts 30 for adjusting tracks vertically, and other means such as bolts 31 and 32 for adjusting and holding same in vertical position. Posts 28 have adjustable members 33, carrying rollers 33^a for supporting tracks, and bolts 34--34 for vertically adjusting members 33 and thereby the tracks; also bolts 32--32 for maintaining tracks in vertical position. Posts or pedestals 28 have top surfaces 37 which are inclined slightly up-

ward to elevate rollers 25 and thereby permit tracks to be removed. Post 29 has a wheel 29^a for serving as a stop to limit backward movement of table. Posts 27 and 28 are preferably connected together in pairs by cross beams 40.

Thus it will be seen that the entire table may be moved out to permit changing wire by operating motor 15, and then moved back 10 by reversing motor, front edge of table normally resting with wheels 21, 22 and 23 on tracks 13, 11 and 12, respectively, and rear of table resting with wheels 25 on track surfaces 37 of pedestals 28.

15 Inasmuch as table is preferably shaken by shaking mechanism, table sections 1 and 1^a are preferably mounted at upper ends of flexible members 41—41 whose lower ends are connected to and supported by side channel members 42—42, below which the various track wheels 21, 22, etc. are mounted, whereby table member 1 may be shaken relatively to members 42—42. The shaking mechanism shown herein comprises a vibratory 25 member 43 mounted on a rock shaft 44 operated by vibratory member 47 actuated by driving members 48 and 49. Inasmuch as said shaking mechanism is shown, described and claimed in another application of mine, 30 executed of even date herewith, Serial No. 648,962, filed July 2, 1923, shaking mechanism for Fourdrinier machines, it will not be further described nor claimed herein.

In accordance with present invention, the 35 feed end of the table and the pulp holding and feeding devices may be adjusted vertically and in such relation as to cooperate properly in their various adjustments. This adjustment may be secured by means of 40 suitable elevating devices and connections for accomplishing the desired purposes. As an advantageous arrangement I have shown an electric motor 65 mounted on the top member 66 forming with posts 67^a frame-work on which the pulp holding and feeding devices are mounted. Motor 65 is geared to power shaft 68 so as to drive same and shaft 68 is connected by sprocket chain 69 with supplemental power shaft 70. The 45 power shafts 68 and 70 raise and lower the feed end of the table 1 and feed box 71 through suitable mechanism preferably controlling same, so that they shall rise and fall together in proper relationship, and also 50 so that the feed box shall be tilted toward the table as it rises and restored to level position as it falls. The mechanism shown for accomplishing this result comprises two sets of vertically adjustable yokes 73—73, 55 and 74—74, whereof the yokes 73—73 are raised and lowered by plunger 73^a, having a worm and wheel connection with shaft 86, and whereof yokes 74—74 are actuated by plunger 74^a (Fig. 11), having similar worm 60 and wheel connection with shaft 70.

Yokes 73 are connected with hangers 76 which engage the ends of projecting members 77 on a cross beam 78 which extends underneath and engages feed box frame pieces 79—79, so that raising and lowering of yokes 73 will elevate and lower feed box 71.

Yokes 74 are connected with hangers 80 whose lower ends engage projections 81 on the feed end of table section 1, whereby raising and lowering of yokes 74 will raise and 75 lower feed end of table, whereby it will be seen feed box 71 and feed end of table will rise and fall together.

As a matter of further and specific improvement, provision is made for tilting feed 80 box 71 so that it will incline down toward the table as it and the table rise. For this purpose I show guideways 83—83 and 84—84 on end posts 67 and slide pins or rollers 85 and 86, the former on side frames 87 on feed box 71, and the latter on frames 88 on hangers 88^a extending down below feed box 71, being preferably formed integral with frames 79. Guideways 83 are preferably inclined inwardly and upwardly, and guideways 84 outwardly and upwardly, as shown in Fig. 7, whereby feed box 71 will in effect be tilted substantially about the feed end of table as both rise and fall, thus insuring proper feed of pulp and proper cooperation of devices in the upward and downward adjustment. Guideways 83 may be adjusted by screw bolts 83^a and guideways 84 by screw bolts 84^a.

The breast roll on table is preferably made 100 adjustable lengthwise of the table to facilitate applying a new wire and for other purposes. In the arrangement shown, said roll is mounted on slides arranged to slide in guideways 92 and provided with a rack 93 meshing with a pinion 94 on shaft 95 also carrying gear 96 meshing with pinion 97 turned by handle 98, whereby rotation of handle 98 will adjust breast wheel 90 lengthwise of the table.

Certain subject matter of this application is disclosed and claimed broadly in co-pending applications of mine Serial Nos. 595,258, filed October 18, 1922; 648,959, 115 648,961, 648,962, filed July 2, 1923, and 205,006, filed July 11, 1927, and hence is not so claimed in this application.

It will be understood that changes and modifications may be made without departing 120 from the spirit of the invention.

What I claim is:

1. A Fourdrinier machine having a laterally removable and vertically adjustable table, means for removing the table and adjusting means for vertically adjusting the feed end of the table, said means being detachably connected with the table and comprising vertically adjustable members and means for elevating and lowering the same, 125 130

said means comprising yokes having connections with the table and vertically adjustable plungers for raising and lowering said yokes.

5. 2. A Fourdrinier machine having a laterally removable and vertically adjustable table, means for removing the table and adjusting means for vertically adjusting the feed end of the table, said means being detachably connected with the table and comprising vertically adjustable members and means for elevating and lowering the same, said means comprising yokes having connections with the table and vertically adjustable plungers for raising and lowering said yokes, and worm and wheel connections for driving said yokes.

20. 3. A Fourdrinier machine having a laterally removable and vertically adjustable table, means for removing the table and adjusting means for vertically adjusting the feed end of the table, said means being detachably connected with the table and comprising vertically adjustable members and means for elevating and lowering the same, said means comprising yokes having connections with the table and vertically adjustable plungers for raising and lowering said yokes, worm and wheel connections for driving said yokes, and a power generator for driving said worm and wheel connections.

25. 4. A Fourdrinier machine having a laterally removable and vertically adjustable table, means for removing the table and adjusting means for vertically adjusting the feed end of the table, said means being detachably connected with the table, and means for adjusting the paper material holding and feeding devices, said means comprising devices for raising and lowering the paper material holding and feeding devices and means for tilting the same as they are raised and lowered.

30. 5. A Fourdrinier machine having a laterally removable and vertically adjustable table, means for removing the table and adjusting means for vertically adjusting the feed end of the table, said means being detachably connected with the table, and means for adjusting the paper material holding and feeding devices, said means comprising devices for raising and lowering the paper material holding and feeding devices and means for tilting the same as they are raised and lowered, said tilting means comprising guideways and pins traveling in said guideways.

35. 6. A Fourdrinier machine having a laterally removable and vertically adjustable table, means for removing the table and adjusting means for vertically adjusting the feed end of the table, said means being detachably connected with the table, and means for adjusting the paper material holding and feeding devices, said means comprising

ing devices for raising and lowering the paper material holding and feeding devices and means for tilting the same as they are raised and lowered, said tilting means comprising guideways and pins traveling in said guideways, said guideways being angularly adjusted and provided with adjusting means.

7. 7. A Fourdrinier machine having a laterally removable and vertically adjustable table, means for removing the table and adjusting means for vertically adjusting the feed end of the table, said means being detachably connected with the table and comprising vertically adjustable members, means for elevating and lowering the same, and means for vertically adjusting the paper material holding and feeding devices, said means comprising yokes engaging the supporting frame of the paper material holding and feeding devices and means for adjusting said yokes.

20. 8. A Fourdrinier machine having a laterally removable and vertically adjustable table, means for removing the table and adjusting means for vertically adjusting the feed end of the table, said means being detachably connected with the table and comprising vertically adjustable members, means for elevating and lowering the same, and means for vertically adjusting the paper material holding and feeding devices, said means comprising yokes engaging the supporting frame of the paper material holding and feeding devices and means for adjusting said yokes, said means comprising vertically adjustable plungers and means for raising and lowering the same.

25. 9. A Fourdrinier machine having a laterally removable and vertically adjustable table, means for removing the table and adjusting means for vertically adjusting the feed end of the table, said means being detachably connected with the table and comprising vertically adjustable members, means for elevating and lowering the same, and means for vertically adjusting the paper material holding and feeding devices, said means comprising yokes engaging the supporting frame of the paper material holding and feeding devices and means for adjusting said yokes, said means comprising vertically adjustable plungers and means for raising and lowering the same, said raising and lowering means being actuated by the devices for driving the raising and lowering means for the table.

30. 10. A Fourdrinier machine having independently mounted and vertically adjustable feed box and means for tilting the same.

35. 11. A Fourdrinier machine having independently mounted and vertically adjustable feed box and also having means for tilting said feed box as it is vertically adjusted.

12. A Fourdrinier machine having a vertically adjustable table and an independently

- and vertically adjustable feed box and also having means for tilting the feed box.
13. A Fourdrinier machine having a vertically adjustable table and an independently and vertically adjustable feed box and means for tilting the feed box as it is vertically adjusted. 70
14. A Fourdrinier machine having a vertically adjustable table and a vertically adjustable feed box and means for adjusting the table and feed box simultaneously and also having means for tilting the feed box independently of the vertical adjustment of the table. 75
15. A Fourdrinier machine having a vertically adjustable table and a vertically adjustable feed box and means for adjusting the table and feed box simultaneously and also having means for tilting the feed box relatively to the table, as it is adjusted vertically. 80
16. A Fourdrinier machine having a vertically adjustable table and also having a vertically adjustable feed box in combination with detachable means for engaging and vertically adjusting the feed end of the table and means for vertically adjusting and tilting the feed box. 85
17. A Fourdrinier machine having a vertically adjustable table and a vertically adjustable feed box in combination with detachable means for raising and lowering the feed end of the table, means for raising and lowering the feed box and means for tilting the feed box as it is raised and lowered. 90
18. A Fourdrinier machine having an independently mounted and vertically adjustable feed box in combination with means for raising and lowering said feed box and means for tilting or inclining the feed box as it is raised and lowered. 95
19. A Fourdrinier machine having an independently mounted and vertically adjustable feed box in combination with means for raising and lowering the same and inclined guideways with cooperating devices for tilting or inclining the feed box as it is raised and lowered. 100
20. A Fourdrinier machine having an independently mounted and vertically adjustable feed box in combination with a frame work for supporting the feed box, yokes for supporting said frame work and connections between said yokes and frame work. 105
21. A Fourdrinier machine having an independently mounted and vertically adjustable feed box in combination with a frame work for supporting the feed box, yokes for supporting said frame work and connections between said yokes and frame work, and guide means for tilting or inclining the feed box as it is raised and lowered by said yokes. 110
22. A Fourdrinier machine having an independently mounted and vertically adjustable feed box and also having a frame sup- 115
- porting said feed box in combination with a cross member below and supporting said frame and projecting beyond the sides thereof, vertically arranged connections engaging said cross member and adapted for vertical adjustment so as to raise and lower the cross member and means for vertically adjusting said connections. 120
23. A Fourdrinier machine having an independently mounted and vertically adjustable feed box and also having a frame supporting said feed box in combination with a cross member below and supporting said frame projecting beyond the sides thereof, vertically arranged connections engaging said cross member and adapted for vertical adjustment so as to raise and lower the cross member and means for vertically adjusting said connections and guide means for engaging said supporting frame and tilting the same as said frame is raised and lowered. 125
24. A Fourdrinier machine having a detachable and vertically adjustable table and also having an independently mounted and vertically adjustable feed box in combination with means for simultaneously adjusting the table and feed box and tilting the latter. 130
25. A Fourdrinier machine having a detachable and vertically adjustable table in combination with means for vertically adjusting said table comprising connections for engaging the feed end of the table, yokes engaging said connections and means for vertically adjusting said yokes. 135
26. A Fourdrinier machine having a detachable and vertically adjustable table in combination with means for vertically adjusting said table comprising connections for engaging the feed end of the table, yokes engaging said connections and means for vertically adjusting said yokes, said last mentioned means comprising threaded plungers and worm and wheel connections for turning and adjusting said plungers. 140
27. In a machine of the class described, the combination of a table, an adjustable feed box, and means for adjusting the feed box to incline the same relative to the table. 145
28. In a machine of the class described, the combination of a vertically adjustable table, and adjustable feed box, and means for adjustably inclining the feed box relatively to the table as the same is adjusted vertically. 150
29. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, said means comprising yokes having connections with the table and vertically ad- 155

justable plungers for raising and lowering said yokes, and means for shaking the table.

30. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, said means comprising yokes having connections with the table and vertically adjustable plungers for raising and lowering said yokes, worm and wheel connections for driving said yokes, and means for shaking the table.

31. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, said means comprising yokes having connections with the table and vertically adjustable plungers for raising and lowering said yokes, worm and wheel connections for driving said yokes, a power generator for driving said worm and wheel connections, and means for shaking the table.

32. A Fourdrinier machine having a laterally removable, shakable and vertically adjustable table, means for removing the table and adjusting means for vertically adjusting the feed end of the table, said means being detachably connected with the table, means for adjusting the paper material holding and feeding devices, said means comprising devices for raising and lowering the paper material holding and feeding devices, means for tilting the same as they are raised and lowered, and means for shaking the table.

33. A Fourdrinier machine having a laterally removable, shakable and vertically adjustable table, means for removing the table and adjusting means for vertically adjusting the feed end of the table, said means being detachably connected with the table, means for adjusting the paper material holding and feeding devices, said means comprising devices for raising and lowering the paper material holding and feeding devices, means for tilting the same as they are raised and lowered, said tilting means comprising guideways and pins traveling in said guideways, and means for shaking the table.

34. A Fourdrinier machine having a laterally removable, shakable and vertically adjustable table, means for removing the table and adjusting means for vertically adjusting the feed end of the table, said means being detachably connected with the table, means for adjusting the paper material

holding and feeding devices, said means comprising devices for raising and lowering the paper material holding and feeding devices, means for tilting the same as they are raised and lowered, said tilting means comprising guideways and pins traveling in said guideways, said guideways being angularly adjusted and provided with adjusting means, and means for shaking the table.

35. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, means for vertically adjusting the paper material holding and feeding devices, said means comprising yokes engaging the supporting frame of the paper material holding and feeding devices, means for adjusting said yokes, said means comprising vertically adjustable plungers and means for raising and lowering the same, and means for shaking the table.

36. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, means for vertically adjusting the paper material holding and feeding devices, said means comprising yokes engaging the supporting frame of the paper material holding and feeding devices and means for adjusting said yokes, said means comprising vertically adjustable plungers and means for raising and lowering the same, said raising and lowering means being actuated by the devices for driving the raising and lowering means for the table, and means for shaking the table.

37. A Fourdrinier machine having a laterally removable, shakable and vertically adjustable table, and also having vertically adjustable paper material holding and feeding devices, means for adjusting said table and paper material holding and feeding devices vertically in unison, said means comprising a power generator and connections between the same and said raising and lowering mechanism, said power transmitting connection comprising vertically adjustable yokes engaging the table and the frame of the paper material holding and feeding devices, plungers for vertically adjusting the yokes and connections between said plungers and the power means, and means for shaking the table.

38. A Fourdrinier machine having a laterally removable, shakable and vertically ad-

justable table, means for removing the table and adjusting means for vertically adjusting the feed end of the table, said means being detachably connected with the table 5 and comprising vertically adjustable members, means for elevating and lowering the same, said means comprising yokes having connections with the table and vertically adjustable plungers for raising and lowering said yokes, and shaking means comprising vibratory members detachably connected to said table.

39. A Fourdrinier machine having a laterally removable, shakable and vertically adjustable table, and also having vertically adjustable paper material holding and feeding devices, means for adjusting said table and paper material holding and feeding devices vertically in unison, said means comprising a power generator and connections between the same and said raising and lowering mechanism, said power transmitting connection comprising vertically adjustable yokes engaging the table and the 20 frame of the paper material holding and feeding devices, plungers for vertically adjusting the yokes and connections between said plungers and the power means, and shaking means comprising vibratory members detachably connected to said table.

In witness whereof, I hereunto subscribe my name this 26th day of May, A. D., 1923.

ALONZO ALDRICH.
